UNITED STATES PATENT OFFICE

124,744

DESIGN FOR A KITCHEN CONTAINER

Adam T. Kozlowski, Cohoes, N. Y.

Application May 13, 1940, Serial No. 92,339

Term of patent 7 years

To all whom it may concern:

Be it known that I, Adam T. Kozlowski, a citizen of United States of America, residing at Cohoes, in the county of Albany and State of New York, have invented a new, original, and ornamental Design for a Kitchen Container, of which the following is a specification, reference being had to the accompanying drawing, forming part thereof, wherein:

I claim:

The ornamental design for a kitchen container, as shown,

ADAM T. KOZLOWSKI.
